KERF-CUTTING MACHINE

Thomas E. Pray, Chicago, Ill., assignor to Goodman Manufacturing Company, Chicago, Ill., a corporation of Illinois

Application August 7, 1936, Serial No. 94,738

16 Claims. (Cl. 262—28)

This invention relates to improvements in kerf-cutting machines of the track mounted type adapted to cut out dirt rashes or bands in the mine wall along the mine bottom or at various elevations with respect thereto.

The principal objects of my invention are to provide a mining machine of the class described which may cut above and below dirt rashes or bands of varying thicknesses in the coal seam.

Another object of my invention is to provide a novel means for supporting the cutter bars for adjustment with respect to each other and with respect to their supporting frame, together with a novel means for adjusting the cutter bars and holding them in adjusted relation with respect to each other.

My invention may be more clearly understood with reference to the accompanying drawings wherein:

Figure 1 is a top plan view of a mining machine constructed in accordance with my invention;

Figure 2 is an enlarged fragmentary side elevation of the forward portion of the machine shown in Figure 1 with parts broken away and shown in longitudinal section in order to more clearly illustrate certain details of my invention;

Figure 3 is an enlarged fragmentary plan view of the forward portion of the device shown in Figure 1 with certain parts broken away and shown in horizontal section;

Figure 4 is a fragmentary side elevation of the forward portion of the device shown in Figure 1, drawn to the same scale as Figure 2, but with certain other parts broken away and shown in longitudinal section;

Figure 5 is a fragmentary sectional view taken substantially along lines 5—5 of Figure 3;

Figure 6 is a fragmentary sectional view taken substantially along lines 6—6 of Figure 2;

Figure 7 is a sectional view taken substantially along lines 7—7 of Figure 2;

Figure 8 is a sectional view taken substantially along lines 8—8 of Figure 2;

Figure 9 is a sectional view taken substantially along lines 9—9 of Figure 2;

Figure 10 is an enlarged detail fragmentary plan view of a portion of the upper cutter bar; and

Figures 11 and 12 are diagrammatic views of the machine showing the cutter bars in various operative positions.

Referring now in particular to the drawings and the details of the embodiment of my invention illustrated therein, a track mounted truck 10 is provided which has a turntable 11 mounted

at its forward end. Said turntable forms a support for a cutting element generally indicated by reference character 12 and including a pair of parallel spaced projecting cutter bars 13 and 14.

The truck 10, besides serving as a movable support means for the cutting element, also serves as a power driven means for feeding the cutter bars 13 and 14 into the coal by movement along the track. The turntable 11 forms a means for positioning said cutter bars in the desired position with respect to the coal face for cutting and also forms a means for feeding said cutter bars across the coal face in a manner well known to those skilled in the art and not herein shown or described since it is no portion of my present invention.

The cutting element 12 includes an elevating frame 15 which is mounted on the turntable 11 in a pair of parallel spaced guides 16, 16 for vertical adjustment with respect thereto. A forwardly projecting cutter frame 17 is pivotally mounted on said elevating frame for movement about a horizontal transverse axis disposed adjacent the forward end thereof. Said cutter frame has a motor 18 secured thereto and extending rearwardly therefrom between the sides of said elevating frame. A suitable adjusting screw, generally indicated by reference character 19, is provided for adjusting the angle of said cutter frame with respect to said elevating frame and the angle of the cutter bars 13 and 14 with respect to the ground. Said adjusting screw and the means for operating it is only herein referred to generally inasmuch as it is of a usual construction and is no portion of my present invention.

The elevating frame 15 is adjustably moved with respect to the turntable 11 by means of a transverse shaft 20 coaxial with the axis of pivotal movement of said cutter frame. Worms 21, 21 are secured to opposite ends of said transverse shaft and mesh with and drive worm gears 22, 22 on the forward ends of longitudinally extending shafts 23, 23 (see Figures 2 and 5). Said longitudinally extending shafts have parallel spaced pinions 24, 24 keyed thereto which are adapted to mesh with vertical racks 25, 25 extending upwardly along the guides 16, 16. Said worms and worm gears are of the self-locking type for holding said elevating frame in fixed relation with respect to said turntable in the usual manner.

The transverse shaft 20 is driven from the motor 18 by means of a jaw clutch member 26

and a helical gear train 27 driven from a longitudinal shaft 28. Said longitudinal shaft is reversely driven through suitable reverse gearing which includes a pair of friction clutches 29, 29 5 on a longitudinal shaft 30 and gear trains 31 and 32 driven therefrom so that when one of said gear trains is connected with said shaft by its respective friction clutch 29 the longitudinal shaft 28 will be driven in one direction, and 10 when the other gear train is connected with the shaft 30, the longitudinal shaft 28 will be driven in an opposite direction. The shaft 28 is in turn driven from the forward end of the motor 18 by means of a suitable spur gear train generally indicated by reference character 33.

The cutter frame 17 is provided with a pair of parallel spaced guiding tongues 34, 34 which extend outwardly therefrom and depend from opposite sides thereof forwardly of the forward 20 end of the truck (see Figure 3). Said guiding tongues are adapted to register for engagement with guide grooves 35, 35 formed in a pair of parallel spaced support members 35^a, 35^a extending rearwardly and outwardly from a support 25 frame 36 for the cutter bar 13. Said support frame is likewise provided with a pair of parallel spaced guiding tongues 37, 37 extending laterally from the outer sides of the support members 35^a, 35^a which are adapted to engage suitable 30 guide grooves 38, 38 formed in support members 38^a, 38^a extending rearwardly from a supporting frame 39 for the cutter bar 14.

The forward end of the supporting frame 36 has an adjusting screw 40 pivotally connected 35 thereto which is threaded within a threaded sleeve 41, which sleeve in turn is threaded within a threaded hub of a worm gear 42. Said worm gear is journaled in the forward end of the cutter frame 17 in a suitable manner and is meshed 40 with and driven from a worm 43 on the forward end of the longitudinally extending shaft 28 (see Figure 3). Said worm is selectively connected with said shaft by means of a suitable jaw clutch member 44.

With reference now in particular to the details of the cutter bar supporting means and several of the novel features of my invention, the upper cutter bar 13 is mounted in a frame member 50 having an annular shouldered portion 51 adapted 50 to engage an inwardly extending annular flange 52 of the supporting frame 36. Said shouldered portion is held in engagement with said flange by means of an annular ring 53 secured to the upper side of said frame member in a suitable 55 manner.

The frame member 50 is provided with parallel spaced inwardly disposed depending walls 54, 54 at its forward end. The space between said walls forms a slot which is adapted to be engaged by an 60 upwardly projecting member 55 of the lower cutter bar 14. Said member is formed integral with a cutter bar support member 56 for the lower cutter bar 14 for guiding said last named cutter bar for adjustable movement towards or from 65 the upper cutter bar 13 and for holding said cutter bars so they may be pivotally moved together.

The cutter bar support member 56 is similar to the cutter bar support member 50 and is held in 70 engagement with an annular flange 57 of the supporting frame 39 by means of an annular ring 59 secured to the upper side of said cutter bar support member and abutting the upper surface of said annular flange.

Suitable means are provided for locking the

cutter bars 13 and 14 from pivotal movement, which means, as herein shown, comprises a locking pin 60 adapted to engage any one of a plurality of apertures formed in the outer periphery of the annular ring 53. Said locking pin is engaged with or disengaged from the desired aperture by means of a hand lever 62 pivoted to the support frame 36 on a pivotal pin 63 and having its free end engaging said locking pin. Thus, said cutter bars may be pivotally moved together 10 about the axis of the frame members 50 and 56 to permit the disposal of the lower cutter bar along the bottom to one side of the track and thus permit a kerf to be cut by the lower cutter bar along the mine bottom to each side of and in 15 front of the track.

The upper cutter bar 13 is mounted in horizontally disposed slots 64, 64 on opposite sides of the walls 54, 54 for adjustable movement with respect to said support member. A suitable adjusting screw 65 is threaded in said cutter bar and abuts the forward end of said support member and forms a means for taking up slack on a cutter chain 66 movable about said cutter bar.

The lower cutter bar 14 is mounted in the 25 cutter bar support frame 56 in a similar manner and adjustment is effected by means of an adjusting screw 67 which serves to permit the taking up of slack in a cutter chain 68 movable about said cutter bar.

The cutter chain 66 is trained around and driven from a drive sprocket 69 on the lower end of a sleeve 70, which sleeve is journaled in the frame member 50 by means of suitable ball bearings in a usual manner.

In a like manner, the cutter chain 68 is trained around a drive sprocket 72 on the lower end of a sleeve 73, which sleeve is journaled in the cutter bar support member 56 on suitable ball bearings in a usual manner.

The sleeves 70 and 73 are internally splined and are adapted to be slidably engaged by a splined shaft 75. Said shaft in turn slidably engages a splined sleeve 76 journaled in the cutter frame 17 and having a bevel gear 77 mounted 45 thereon. Said bevel gear is meshed with and driven from a bevel pinion 78 on the forward end of the longitudinally extending shaft 30 for driving said cutter chains about said cutter bars.

Adjustment of the cutter bar 14 with respect 50 to the cutter bar 13 is effected by means of an adjusting screw 79 pivotally mounted in the cutter bar support frame 56 on a pivotal pin 80 disposed forwardly of the guides 38, 38 and rearwardly of the guides formed by the walls 54, 54 (see Figures 2 and 7). Said adjusting screw is threaded within a threaded hub of a worm gear 81 which worm gear is journaled on its hub in a bearing and support frame 83 secured to and depending from the frame member 50. A worm 60 84 meshes with the worm gear 81 and may be rotatably driven by a suitable hand crank in a usual manner.

With reference now in particular to Figures 11 and 12, illustrating the cutter bars in several 65 operative positions, in Figure 11 the lower cutter bar 14 is positioned for cutting adjacent the ground, which may be along the bottom of the dirt band, while the upper cutter bar 13 is positioned for cutting along the top of the dirt band so that 70 the two bars may completely cut out the dirt band in a coal seam. It is apparent from the foregoing that during the cutting operation the cutter bars operate as a unit and that they are only vertically adjusted with respect to each other 75

where the thickness of the dirt band varies, which condition usually occurs only in different parts of the mine and not in the same working place.

In Figure 13 the cutting element has been raised to an extreme uppermost position along the guides 16, 16 and the cutter bars 13 and 14 are spaced closer together than in Figure 1 for cutting out a band of a different thickness from the center of the coal seam. It should herein be understood that, if desired, the entire cutting mechanism may be inverted in the guides 16, 16 to permit the lower cutter bar 14 to cut a kerf along the roof and permit the upper cutter bar 13 to cut a kerf spaced downwardly therefrom, or a cutting element of the type having a rotatable head such as is shown in Patent No. 2,027,456, granted to William W. Sloane on January 14, 1936, may be used to permit the cutter bars to be inverted to cut along the roof as well as along the bottom.

It may now be seen that a new and improved mining machine has been provided having a pair of parallel spaced cutter bars adapted to cut out dirt seams in the mine wall of varying thicknesses and that said cutter bars are supported in a simple and efficient manner for adjustment with respect to each other and for adjustment with respect to an overhanging supporting frame and also for adjustment with respect to a supporting truck which effects an arrangement whereby dirt bands may be cut out in varying locations in the mine wall. It may also be seen that a new and improved support and adjusting means has been provided for the cutter bars which is of a simplified construction and permits the cutter bars to cut as a unit.

While I have herein shown and described one form in which my invention may be embodied, it will be understood that the construction thereof and the arrangement of the various parts may be altered without departing from the spirit and scope thereof. Furthermore, I do not wish to be construed as limiting myself to the specific embodiment illustrated, excepting as it may be limited in the appended claims.

I claim as my invention:

1. In a mining machine, a frame, and a pair of cutter bars having cutter chains movable thereabout, mounted on said frame for simultaneous adjustable pivotal movement about coaxial vertical axes disposed adjacent their rearward ends, means for mounting said cutter bars for simultaneous vertical adjustment with respect to said frame and means interposed between said cutter bars for adjustably moving one of said cutter bars with respect to the other.

2. In a mining machine, a frame, and a pair of cutter bars having cutter chains movable thereabout, mounted on said frame for adjustment about coaxial vertical axes disposed adjacent their rearward ends, said cutter chains being driven from a common drive shaft coaxial with their axis of pivotal adjustment, means for mounting said cutter bars for simultaneous vertical adjustment with respect to said frame, means interposed between said cutter bars for adjustably moving one of said cutter bars with respect to the other and a slidable guide connection between said cutter bars to hold said cutter bars for simultaneous pivotal adjustment with respect to said frame.

3. In a track mounted mining machine, a truck, a turntable thereon, a frame mounted on said turntable for vertical adjustment with respect thereto, and a pair of parallel spaced cutter bars projecting from said frame, said cutter bars having cutter chains movable thereabout, means for mounting said cutter bars for aligned vertical adjustment with respect to each other, and a slidable guide connection between said cutter bars to hold said cutter bars for pivotal adjustment together.

4. In a track mounted mining machine, a truck, a turntable thereon, a frame projecting forwardly of said turntable and mounted thereon for vertical adjustment with respect thereto, a pair of parallel spaced depending horizontal cutter bars mounted on said frame for adjustment about a common vertical axis and for adjustment towards and from said frame, and means interposed between said cutter bars for adjustably moving one of said cutter bars with respect to the other.

5. In a track mounted mining machine, a truck, a turntable thereon, a frame projecting forwardly of said turntable and mounted thereon for vertical adjustment with respect thereto, a pair of parallel spaced depending horizontal cutter bars mounted on said frame for simultaneous adjustable movement about a common vertical axis to permit the lowermost of said cutter bars to cut below the level of the rail along the mine bottom, said cutter bars being mounted for adjustment towards and from said frame, and means interposed between said cutter bars for adjustably moving said lowermost cutter bar towards and from said upper cutter bar.

6. In a mining machine, a frame, a pair of cutter bars having cutter chains movable thereabout mounted on said frame for adjustment about a common vertical axis disposed adjacent their rearward ends, and a supporting and guiding connection between said frame and cutter bars to permit said cutter bars to be adjusted towards and from said frame and towards and from each other comprising a pair of parallel spaced guides depending from said frame, a cutter bar supporting frame having said first-mentioned cutter bar pivotally connected thereto and projecting therefrom, and a slidable guiding connection between said guides and frame, a pair of guides on said cutter bar supporting frame, and a second cutter bar support frame for supporting said other cutter bar and having a slidable guiding connection with said guides on said first-mentioned cutter bar supporting frame.

7. In a mining machine, a frame, a pair of cutter bars having cutter chains movable thereabout mounted on said frame for adjustment about a common vertical axis disposed adjacent their rearward ends, and a supporting and guiding connection between said frame and cutter bars to permit said cutter bars to be adjusted towards and from said frame and towards and from each other comprising a pair of parallel spaced guides depending from said frame, a cutter bar supporting frame having said first-mentioned cutter bar pivotally connected thereto and projecting therefrom, and a slidable guiding connection between said guides and frame, a pair of guides on said cutter bar supporting frame, and a second cutter bar support frame for supporting said other cutter bar and having a slidable guiding connection with said guides on said first-mentioned cutter bar supporting frame, and mechanisms disposed forwardly of and intermediate said guides for moving said cutter bars towards and from said frame and towards and from each other.

8. In a mining machine, a frame, a pair of cutter bars having cutter chains movable there-

- about mounted on said frame for adjustment about a common vertical axis disposed adjacent their rearward ends, and a supporting and guiding connection between said frame and cutter bars to permit said cutter bars to be adjusted towards and from said frame and towards and from each other comprising a pair of parallel spaced guides depending from said frame, a cutter bar supporting frame having said first-mentioned cutter bar pivotally connected thereto and projecting therefrom, and a slideable guiding connection between said guides and frame, a pair of guides on said cutter bar supporting frame, and a second cutter bar support frame for supporting said other cutter bar and having a slideable guiding connection with said guides on said first-mentioned cutter bar supporting frame, adjusting mechanism disposed forwardly of said guides and interposed between said frame and first-mentioned cutter bar supporting frame for moving both of said cutter bars towards and from said frame, and other adjusting mechanism interposed between said cutter bars for moving said cutter bars towards and from each other.
- 25 9. In a track mounted mining machine, a truck, a turntable thereon, a frame mounted on said turntable for vertical adjustment with respect thereto, a pair of parallel spaced guides depending from said frame, a cutter bar supporting frame mounted for movement therealong, and means disposed forwardly of and intermediate said guides for moving said supporting frame towards and from said first-mentioned frame, said support frame having a chain carrying cutter bar projecting therefrom and mounted for pivotal movement with respect thereto about an axis perpendicular to its cutting plane, a pair of parallel spaced guides extending along said support frame, said guides having a second cutter bar supporting frame guided for movement therealong, and said second-mentioned support frame having a projecting chain carrying cutter bar mounted thereon for pivotal movement with respect thereto about an axis perpendicular to its cutting plane, and means disposed forwardly of said guides for adjustably moving said cutter bars towards and from each other.
- 30 10. In a track mounted mining machine, a truck, a turntable thereon, a frame mounted on said turntable for vertical adjustment with respect thereto, a pair of parallel spaced guides depending from said frame, a cutter bar supporting frame mounted for movement along said guides, and means disposed forwardly of and intermediate said guides for moving said supporting frame towards and from said first-mentioned frame, said support frame having a chain carrying cutter bar projecting therefrom and mounted for pivotal movement with respect thereto about an axis perpendicular to its cutting plane, a pair of parallel spaced guides extending along said support frame, said guides having a cutter bar supporting frame guided for movement therealong, and said second-mentioned support frame having a projecting chain carrying cutter bar mounted thereon for pivotal movement with respect thereto about an axis perpendicular to its cutting plane, means disposed forwardly of said guides for adjustably moving said cutter bars towards and from each other, and slideable guiding means interposed between said cutter bars and disposed forwardly of said guides for holding said cutter bars for pivotal movement as a unit when in various positions of adjustment with respect to each other.
- 35 11. In a track mounted mining machine, a truck, a turntable thereon, a frame mounted on said turntable for vertical adjustment with respect thereto, a pair of parallel spaced guides depending from said frame, a cutter bar support frame mounted for movement therealong, and means disposed forwardly of and intermediate said guides for moving said supporting frame towards and from said first-mentioned frame, said support frame having a chain carrying cutter bar projecting therefrom and mounted for pivotal movement with respect thereto about an axis perpendicular to its cutting plane, a second cutter bar support frame disposed beneath said first-mentioned cutter bar support frame and having a projecting chain carrying cutter bar mounted thereon for pivotal movement with respect thereto about an axis perpendicular to its cutting plane, and means interposed between said cutter bars for adjustably moving said second-mentioned cutter bar towards or from said first-mentioned cutter bar.
- 40 12. In a track mounted mining machine, a truck, a turntable thereon, a frame mounted on said turntable for vertical adjustment with respect thereto, a pair of parallel spaced guides depending from said frame, a cutter bar support frame mounted for movement therealong, and means disposed forwardly of and intermediate said guides for moving said support frame towards and from said first-mentioned frame, said support frame having a chain carrying cutter bar projecting therefrom and mounted for pivotal movement with respect thereto about an axis perpendicular to its cutting plane, another cutter bar support frame disposed beneath said first-mentioned cutter bar support frame and having a projecting chain carrying cutter bar mounted thereon for pivotal movement with respect thereto about an axis perpendicular to its cutting plane, means interposed between said cutter bars for adjustably moving said second-mentioned cutter bar towards or from said first-mentioned cutter bar, and slideable guide means interposed between said cutter bars for guiding said cutter bars for movement towards or from each other and holding said cutter bars from lateral displacement with respect to each other during the cutting operation.
- 45 13. In a mining machine, a frame, a pair of cutter bars having cutter chains movable thereabout mounted on said frame for adjustment about a common vertical axis disposed adjacent their rearward ends, and a supporting and guiding connection between said frame and cutter bars to permit said cutter bars to be adjusted towards and from said frame and towards and from each other comprising a pair of parallel spaced guides depending from said frame, a cutter bar supporting frame having one of said cutter bars pivotally connected thereto and projecting therefrom, and a slideable guiding connection between said guides and cutter bar support frame, a second cutter bar support frame disposed beneath said first-mentioned frame forming a support means for said other cutter bar, means disposed forwardly of said guides and interposed between said first-mentioned frame and support frame for moving said cutter bars towards or from said frame, and means interposed between said cutter bars for adjustably moving said second-mentioned cutter bar towards and from said first-mentioned cutter bar.
- 50 14. In a mining machine, a base, a frame overhanging the forward end of said base, a cutter

bar mounted for slidable movement towards and from said frame, a second cutter bar mounted for slidable movement towards and from said first cutter bar, means interposed between said frame and first-mentioned cutter bar for moving both of said cutter bars towards and from said frame, and means interposed between said cutter bars for independently moving said second-mentioned cutter bar towards and from said first-mentioned cutter bar.

15. In a mining machine, a base, a frame overhanging the forward end of said base, a pair of guides disposed forwardly of said base and depending from said frame, a cutter bar support frame having guides extending therefrom mounted for movement along said guides, a cutter bar projecting from said frame, another cutter bar support frame having guides extending therefrom guided for movement along the outer side of said guides of said other support frame, a cutter bar projecting from said frame, means interposed between said overhanging frame and first-mentioned cutter bar for moving both of said cutter bars towards and from said frame, 25 and means interposed between said cutter bars for independently moving said second-mentioned cutter bar towards and from said first-mentioned cutter bar.

16. In a mining machine, a frame, a pair of

cutter bars having cutter chains movable thereabout mounted on said frame for adjustment about a common vertical axis disposed adjacent their rearward ends, and a supporting and guiding connection between said frame and cutter bars to permit said cutter bars to be adjusted towards and from said frame and towards and from each other comprising a pair of parallel spaced guides depending from said frame, a cutter bar support frame having one of said cutter bars pivotally connected thereto and projecting therefrom, and a slidable guiding connection between said guides and frame, a second cutter bar support frame disposed beneath said first-mentioned support frame forming a support 15 means for said other cutter bar, means disposed forwardly of said guides and interposed between said first-mentioned frame and support frame for moving said cutter bars towards and from said frame, means interposed between said cutter 20 bars for adjustably moving said second-mentioned cutter bar towards and from said first-mentioned cutter bar, and slidable guide means interposed between said cutter bars for guiding said cutter bars for movement towards or from 25 each other and holding said cutter bars from lateral displacement with respect to each other during the cutting operation.

THOMAS E. PRAY.
